Primary Examiner—Holly H. Baynham
Attorney, Agent, or Firm—Kalish & Gilster[57] **CLAIM**

The ornamental design for a bracket for cleat cleaning brush, as shown and described.

DESCRIPTION

FIG. 1 is a perspective view of a bracket for a cleat cleaning brush showing my new design, the broken lines showing a brush are for illustrative purposes only and form no part of the claimed design;

FIG. 2 is a reduced front elevational view thereof with the rear view being a mirror image;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a reduced environmental top, front perspective view with the broken line showing of a fragmented golf cart being for illustrative purposes only and forming no part of the claimed design.
